UNITED STATES PATENT OFFICE.

JOHN RUST, OF KALAMAZOO, MICHIGAN.

ADJUSTABLE BED.

1,343,985.

Specification of Letters Patent. Patented June 22, 1920.

Application filed July 25, 1919. Serial No. 313,311.

To all whom it may concern:

Be it known that I, JOHN RUST, a citizen of the United States, residing at Kalamazoo, county of Kalamazoo, State of Michigan, have invented certain new and useful 5 Improvements in Adjustable Beds, of which the following is a specification.

This invention relates to improvements in adjustable beds. My present improvements 10 relate more particularly to the type of adjustable bed shown in Letters Patent, No. 1,265,253, issued May 7, 1918, the same being an adaptation and improvement upon the structure there illustrated.

15 The main object of this invention is to provide an improved adjustable bed which is easily adjusted to accommodate the needs of the particular occupant.

Further objects, and objects relating to 20 structural details, will definitely appear from the detailed description to follow.

I accomplish the objects of my invention by the devices and means described in the following specification. The invention is 25 clearly defined and pointed out in the claims.

A structure which is a preferred embodiment of my invention is clearly illustrated in the accompanying drawing forming a 30 part of this specification, in which:

Figure I is a plan view of the bed embodying the features of my invention, portions of the bed spring being omitted.

Fig. II is a side elevation with the bed 35 bottom adjusted to horizontal position as shown in Fig. I.

Fig. III is a side elevation showing the 40 adjustment of the bed as a chair with the foot section in alignment with the seat section.

Fig. IV is a side elevation showing another adjustment of the bed as a chair.

Fig. V is a detail longitudinal section 45 showing the bed tilted, the head of the bed being elevated.

Fig. VI is a detail transverse section on a line corresponding to line 6—6 of Figs. I and II, showing details of the operating means.

50 Fig. VII is a detail vertical section on a line corresponding to line 7—7 of Fig. III, showing special features of the rests or supports.

Fig. VIII is an enlarged section of the 55 locking mechanism, partially in section.

In the drawing similar reference characters refer to similar parts throughout the several views, and the sectional views are taken looking in the direction of the little arrows at the ends of the section lines. 60

Referring to the drawing, the bed frame of the structure illustrated comprises head and foot members 1 and 2, respectively, and side rails 3. The bed bottom comprises the head section 4, seat section 5 and foot section 6. These bottom sections are formed of side pieces connected by suitable cross pieces. The sections are pivotally connected at 7. The spring bottom 8 is continuous, only a portion, however, being 70 illustrated.

Each side rail is provided with a hanger 9 for the actuating shaft 10 which projects at one side to receive the crank 11. The head section is pivoted at 11, the pivot in 75 the structure illustrated being engaged with segments 12 to which the head section is rigidly connected. The segments mesh with the pinions 13 on the adjusting shaft. The shaft is provided with a locking ratchet 80 wheel 14 with which the locking pawl 15 coacts, the pawl being pivoted at 16 for adjustment to and from engaging position and being held in its engaging or locking position by the catch 17 which engages with the 85 pin 18 on one of the hangers. These parts described are in general the same as in my patent referred to.

The foot section is provided with downwardly projecting arms 19 carrying pins 20 90 and having clamping nuts 21 thereon. These arms are connected to the segments by the links 22 which have slots 23 therein engaging these pins, the links being pivoted at 24 to the segments. By the adjusting of 95 these nuts the links may be clamped to the arms or allowed to slide thereon. When clamped to the arms, the head and foot sections are simultaneously adjusted. When the nuts are released a lost motion connection is provided so that the adjustment of the head section may be accomplished, as illustrated in Fig. III, without corresponding adjustment of the foot section. The links 25 are pivoted at 26 to the seat section and slotted at 27 to engage the pins 20. This slotted or lost motion connection permits the adjustment of the foot section, but limits the upward movement of the foot section relative to the seat section, so that 110

after these parts are brought into alinement a continued upward movement will tilt the bed bottom as a whole.

By securing both the links 22 and 25 by 5 means of the clamping nuts additional adjustments of the sections relative to each other are provided so that the bed may be adjusted to a number of positions accommodating the needs or desires of the user.

- 10 10 To support either or both of the seat and foot sections, I provide the rests 28 which are pivotally mounted on the hangers 28' on the side rails 2, clamping nuts 29 being provided for securing the rests in 15 their operative and inoperative positions as may be desired, the nuts clamping the rests against the pins 30, the rests being notched to receive the pin as shown in Fig. VII.

With the parts thus arranged, the bed 20 bottom may be tilted as a whole, either by raising or lowering the head, and may be adjusted to bring the head, seat and foot portions in different relative positions as may suit the needs of the particular occupant.

My improved bed is easily manipulated and adjusted, and securely retained in its adjusted positions.

Having thus described my invention, what 30 I claim as new and desire to secure by Letters Patent is:

1. In an adjustable bed, the combination of a supporting frame, a bed bottom comprising pivotally connected head, seat and foot sections, segments on which said head section is mounted pivotally mounted on said frame, an actuating shaft provided with pinions meshing with said segments, depending arms on said foot section, slotted links 35 connected to said segments, links connected to said seat section, pins on said arms engaging the slots of said links, said pins being provided with clamping nuts whereby said links may be clamped to said arms or permitted to slide thereon, and rests for said seat and foot sections adjustably mounted on said frame to support said sections or permit the adjustment thereof.

2. In an adjustable bed, the combination 50 of a supporting frame, a bed bottom comprising pivotally connected head, seat and foot sections, segments on which said head section is mounted pivotally mounted on said frame, an actuating shaft provided with pinions meshing with said segments, depending arms on said foot section, slotted links 55 connected to said segments, pins on said arms engaging the slots of said links, said pins being provided with clamping nuts whereby said links may be clamped to said arms or permitted to slide thereon, and rests for said seat and foot sections adjustably mounted on said frame to support said sections or permit the adjustment thereof.

- 65 3. In an adjustable bed, the combination

of a supporting frame, a bed bottom comprising pivotally connected head, seat and foot sections, said head section being pivotally mounted on said frame, an adjusting means for said head section, an arm on said foot section, a slotted link connected to said head section, a slotted link connected to said seat section, a pin on said arm engaging the slots of said links, said pin being provided with a clamping nut whereby said link may be clamped to said arm or permitted to slide thereon, and rests for said seat and foot sections mounted on said frame to support said sections or permit the adjustment thereof.

4. In an adjustable bed, the combination 80 of a supporting frame, a bed bottom comprising pivotally connected head, seat and foot sections, said head section being pivotally mounted on said frame, an adjusting means for said head section, an arm on said 85 foot section, a slotted link connected to said head section, a pin on said arm engaging the slot of said links, said pin being provided with a clamping nut whereby said link may be clamped to said arm or permitted to slide 90 thereon, and rests for said seat and foot sections mounted on said frame to support said sections or permit the adjustment thereof.

5. In an adjustable bed, the combination 95 of a supporting frame, a bed bottom comprising pivotally connected head, seat and foot sections, the head section being supported for pivotal adjustment on said frame, a link connecting said head and foot sections, means for securing said link to one section 100 to secure a simultaneous movement of the sections or releasing the link permitting lost motion between the parts, and means limiting the upward swing of said foot section relative to said seat section so that after said 105 seat and foot sections are brought into alinement continued actuation of said head section tilts the bed bottom as a whole.

6. In an adjustable bed, the combination 110 of a supporting frame, a bed bottom comprising pivotally connected head, seat and foot sections, the head section being supported for pivotal adjustment on said frame, lost motion connections for said head and foot sections and said seat and foot sections 115 permitting the raising of said head section while the seat and foot sections are in the same relative relation and the downward adjustment of said foot section without moving the seat section, and means for securing 120 said lost motion connections so that the sections are adjusted together.

In witness whereof, I have hereunto set my hand and seal in the presence of two witnesses.

JOHN RUST. [L. S.]
